Des. 187,912
Patented May 17, 1960

187,912

SWINGING DOOR

Joseph Lucchino, Los Angeles, Calif.

Application December 22, 1959, Serial No. 58,759

Term of patent 14 years

(Cl. D13—1)

Fig. 2

Fig. 1

Fig. 3

I claim:

The ornamental design for a swinging door, as shown.
